TYPE BAR MACHINE

Harley J. Megley, Chicago, Ill.

Application January 28, 1933, Serial No. 653,966

6 Claims. (Cl. 29—24)

This invention relates to a type bar machine and the present application is a continuation in part of my copending application, Serial No. 118,176, filed June 24, 1926.

5 The parent application above identified is directed to a method and machine for moving the slug in a given path and, during its movement in such a path, bodily severing the body of the slug within its height to divide the slug body 10 into a printing head of less than type high and a removed gate-like base. The parent application is further directed to the method of reducing the height of a type-high printing slug to less than type high, said slug having a slug body, 15 which comprises moving the slug by intermittent motion in a given path and during a period of intermission in the movement of the slug operating upon the slug to sever the body of the slug within its height whereby to divide the slug 20 body into a printing head of less than type high and a removed gate-like base, and to a machine of the class described having continuously operating means for moving the printing slug by intermittent motion in a given path and means 25 operable with said continuously operating means for operating upon said slug across its width and during a period of intermission in the movement of the slug to prepare the slug for use in the chased carrier of a printing machine employing 30 slugs which are less than type high. The parent application is still further directed to a machine for reducing to less than type high the height of a type-bar having a printing head of a height less than type high and provided with retention 35 means for engagement in a chased carrier, and a gate-like base by moving the slug in a given path and severing the bar within its height and below the retention means in the head to separate the base from the printing head during 40 the movement of the slug in said path, and to delivering the slugs prepared for use in the chased carrier of a printing machine employing slugs which are less than type high to packing material or to a chased carrier, or other suitable 45 or preferred means.

The present application relates to moving the slugs in a given path and, during the operation of the means for moving the slugs in such a path, operating upon the slug to form retention means for engagement in the chased carrier of the printing machine. The means for moving the slugs in a given path is adapted for continuous operation, and the means for forming the retention means is operable with this continuously operating means. In one illustrated embodiment of the invention, the means for forming the retention means operates upon the slug across its width and, in order to permit this and at the same time not interfere with the continuous operation of the slug moving means

and the retention forming means therewith, the slug is moved by intermittent motion, and the retention forming means operates during a period of intermission in the movement of the slug.

It is to be understood, however, that the present invention is not limited to operation of the retention forming means upon the slug across its width, nor is it to be limited to moving the slug by intermittent motion and operating the retention forming means during a period of intermission of the movement of the slug. The retention forming means may be in the form of complementary wheels or other members between which the slugs are moved by the operation of the machine, and which means imparts a crimped or serpentine formation or otherwise forms the retention means on the slug.

The present invention also contemplates broaching the slug across its width and during a period of intermission in the movement of the slug. The broaching feature is particularly applicable to slugs having printing rules, and the broaches formed in the broaching operation are adapted for receiving cross strips which may be formed to print lines across the lines printed by the slug rules. These cross strips may also bind or tie the slugs together. The broaching and retention forming features are covered broadly by the claims of the parent application above identified, and the claims to these features in the present application are drawn to cover the more specific aspects of these provisions.

Numerous advantages and adaptations of the present invention will be apparent from the following detailed description taken in connection with the accompanying drawings, in which:

Referring to the drawings, the present machine comprises in general the horizontal table 5 mounted upon a suitable base or legs 6 having supporting feet 7.

30 A reel 8, freely journaled at 9 in the framework or base 6, carries a roll of corrugated paper or board or other suitable material in which the slugs or bars are packed. The packing material 12 is placed in roll form on the spindle 10 of the reel 8, and when the material of one roll is exhausted another roll may be placed upon the reel. Slugs or bars of different lengths or packing material of different widths and with different numbers of corrugations per foot may be employed. 35 From the reel 8 the packing material 12 passes up around an idler roller 14 freely journaled at the front edge of one side of the table or top 5 and passing over the roller 14 it travels rearwardly over the table 5 being advanced rearwardly as 40 the slugs are fed thereto by feed mechanism designated generally at 15.

The slugs or bars are arranged upon the table 5 in upright position with their character bearing edges upwardly and in a row 18 (Figure 1), parallel with the rearward path of travel of the paper 12. Pusher or feed means 20 feeds the entire row 18 of bars rearwardly toward a feed mechanism 22 and into successive registration 45 with a channel 86 (Figure 8) in the edge piece 23 along the block 23. The feed mechanism 22 removes the bars from the row 18, one at a time, and feeds them laterally into and through the channel 86, and the reduced and less than type high printing heads with the retention means 50 formed therein are moved from the opposite end of the channel 86 into the successive channels 55 in the paper 12 where the slugs are to be packed in the manner more fully illustrated and described in the parent application.

60 The block 23, and the edge piece 85 thereof, has ribs 86 longitudinally along the sides of the channel 86 for supporting and guiding the overhanging head of the slug, as best shown in Figure 8. 65 Where the overhanging head of the slug is previously formed, these ribs may extend throughout the length of the channel 86, whereas, if the sides of the slugs are milled below the head to form the overhanging head in the movement of the slug through the machine, the ribs may be disposed only beyond the head forming means in the path 70 of movement of the slug from the point of supply to the point of delivery. Where the slugs are delivered directly to the galley, multigraph drum, segment, or the like, instead of to the packing ma-

terial 12, the drum or other holder is mounted at the end of the block 23 where the packing material is now disposed, and is adapted to have its grooves successively registered with the channel 86 to receive the slugs therefrom. In the 5 present instance, the packing material is merely illustrative of any means for receiving the slugs from the channel 86, and it is to be understood that as the printing heads of the slugs leave the channel 86 they may be taken in any suitable or 10 preferred manner for use as and where desired.

The desired operation or combination of operations are performed upon the slug in its movement through the machine without interrupting or interfering with the continuous operation of 15 the machine.

Having now described, in a general way, the main parts of the machine, I shall now proceed to a detailed description of the various parts or 20 mechanisms.

The particular slug shown in Figure 7 comprises the shank 30 and the overhanging head 31. The head 31 has the printing characters 33 and the overall height of the slug is substantially 25 equal to the height of the usual type high slug.

Where slugs of this sort are employed, they are arranged in upright position upon the table 5 in the row 18. The T-shaped slugs may be held in upright position upon the table 5 by positioning the lower ends of the shanks 30 between 30 the prongs 500 of a rack 501. The width of each prong 500 is substantially equal to the distance between the shanks 30 when the slugs are grouped with their heads in engagement as shown, and form spacers for spacing the lower ends of the shanks of the slugs to hold the slugs in upright position. Individual spacer slugs or blocks may, of course, be positioned between the lower ends of the slug shanks 30 for the same purpose. Where the spacer and slug positioning means is 35 in the form of a rack as shown, the prongs of this rack preferably are integrally connected at one end at 502 and the opposite ends of the prongs 500 are free and open from the opposite end of the rack so that the rack may be positioned at 40 the type casting machine and the shanks of the T-shaped slugs moved laterally into position between the prongs 500 laterally of the rack and through the openings between the free ends of the prongs, the rack being moved with the operation of the type casting machine to advance the spaces between the prongs 500 for receiving the slugs as they are discharged from the machine. The outer ends of the prongs 500 preferably are tapered at 503 to facilitate movement of the shanks 30 into the spaces 504 between the prongs. When the desired number of slugs are positioned in the rack, the rack with the slugs in place is positioned upon the table 5 ahead of the follower 20 with the character bearing faces of the overhanging heads 31 facing upwardly as shown in Figure 45 40, and the follower 20 operates to feed the slugs and rack as a unit toward the lateral slug feeding means 22.

The dog 93 which engages the slugs and moves 65 the same laterally from the row 18 operates above the plane of movement of the prongs 500 of the rack to engage the slugs above the prongs 500 for the purpose of moving the slugs laterally from the rack and into the guide 83 and the upper 70 character bearing heads through the guide and from the opposite end thereof. The stopping engagement of the guide with the slugs for positioning the slugs successively in register with the guide groove 86 preferably occurs above 75

and/or beyond the prongs 500 and the guide is open at 505 (Figure 4) to permit the rack to move therethrough as the slugs are removed from the rack. After the last slug is removed, the rack 5 is available in its position rearwardly of the guide 83 for use with another group of slugs.

The follower 20 is adjustably secured by a thumb screw 35 to one end of a bar 36 slidably mounted in a slot 37 in the table 5 for movement parallel with the path of travel of the paper 12 over the table 5. The opposite sides of the bar 36 are grooved and the adjacent sides of the slot 37 have longitudinal tenons fitting in these grooves and holding the bar against upward and downward displacement. The opening 40 in the follower 20, through which the screw 35 passes, is elongated and opens from one end of the follower to permit adjustment of the position of the follower upon the bar 36 and convenient removal 10 and replacement of the follower so that followers of different lengths for slugs of different lengths may be conveniently interchanged.

For the purpose of advancing the follower 20 to feed the entire row 18 of slugs rearwardly toward the lateral feed mechanism 22 the under-surface of the bar 36 has teeth or ridges 38 transversely across the same. These teeth 38 may be formed in a separate strip 39 secured to the under-surface of the bar 36, as shown in Figure 4, or 15 they may be formed directly in the under-surface of the bar 36 itself.

Underlying and mounted for reciprocation beneath the bar 36 is a block 42. This block 42 is of generally channel cross section with out-turned margins 43 at the upper edges of its opposite sides. These out-turned margins 43 overhang strips 44 which may be removably secured to the table 5 and which support the block 42 for sliding movement beneath the bar 36.

Mounted in the channel portion of the block 42, between the opposite sides thereof, is a plate 45 having teeth 46 for engagement with the teeth 38 on the bar 36. The plate 45 is guided for up and down movement in the channel portion of the block and free thereof upon pins 48 secured in the block 42 and engaging in suitable openings in the plate 45. At its forward end the block 42 has a depending ear 49 to which one end of an eccentric rod 50 is pivoted at 52. The opposite end of the eccentric rod 50 has an eccentric strap 53 surrounding an eccentric 54 on the shaft 55 so that, as the shaft 55 is rotated, the block 42 and plate 45 carried thereby will be reciprocated back and forth beneath the bar 36. The block 42 has an opening 56 for accommodating a coiled spring 58, which spring is interposed between the dog plate 45 and a plate member 60 resting upon the eccentric rod 50. In operation, the shaft 55 preferably rotates in the direction indicated by the arrow in Figure 4 and reciprocates the block 42 through the rod 50. The forward movement of the rod 50 and block 42 are accompanied by an upward component of movement. This upward movement of the eccentric rod 50 50 yieldingly forces the plate or dog member 45 upwardly through the spring 58 and the teeth 46 into engagement with the teeth 38 on the bar 36, and the accompanying forward movement of the rod 50 and block 42 shifts or advances the bar 36 rearwardly or to the left in Figure 4 through the engagement of the teeth of the dog member or plate 45 with the teeth on the bar 36.

The rearward movement of the rod 50 is accompanied by a downward component of movement which releases the effort imparted upwardly upon

the plate 45 through the spring 58 and permits the teeth 46 on the plate 45 to disengage and slide yieldingly beneath the teeth 38 without shifting the bar 36 with the forward movement of the rod 50.

Thus the eccentric rod 50 continuously advances the row of slugs 18 rearwardly without releasing the advancing tension with the movement of the rod 50 in the opposite direction, and the accompanying upward and downward movement in the rod 50 is utilized to create and release the advancing engagement between the plate 45 and the bar 36.

While the particular source of power may be varied, the source shown comprises an electric 15 motor 62 mounted upon a shelf 63 at the bottom of the standards or legs 6. The motor shaft has a pulley 64, and suitably journaled in the upper part of the standard framework 6 is a shaft 65 having a relatively large pulley 66. A belt 68, 20 trained about the pulleys 64 and 66 transmits the drive of the motor to the shaft 65. The shaft 65 bears a relatively small pinion 69 which meshes with a relatively large spur gear 70 on the shaft 72 and transmits the drive to the shaft 72 there- 25 through. The shaft 72 also bears a gear 73 which meshes with a gear 74 on the shaft 75 and transmits the drive to this shaft through these gears. The shaft 75 bears a worm gear 76 which meshes with a worm gear 78 on the shaft 55 and drives 30 the same therethrough. The shaft 55 is journaled in bearings on the table 5, one of such bearings being illustrated at 80 in Figure 4.

The feed mechanism 22 comprises a bar 82 reciprocable at right angles to the direction of advancement of the slug row 18 in a guide 83 suitably secured upon the table 5. The guide 83 forms, in effect, a stop for the successive slugs 18. As the slug reaches the guide 83 the stop function thereof registers the overhanging head 40 31 with the groove 86 in the block 23 and face or edge piece 85 along the rear edge of the block 23 and with the bottom of this overhanging head 31 positioned to slide upon the ribs 36' along the bottom of the groove 86 as the slug is fed laterally by the feed mechanism 22.

Pivoted at 90, upon a vertical pin 92 in the bar 82 and movable with the bar, is a dog 93. This dog 93 has a nose which projects out through a slot in the guide 83, and a spring 95 connected 50 between the guide 83 and the dog 93 normally swings the dog into projected position from the guide, as shown in Figure 5, and into engagement with a stop 86.

For the purpose of reciprocating the feed bar 55 82, an arm or lever 98 is pivoted at one end at 99 (Figure 3) on the framework of the machine. The opposite end of this lever 98 is forked or bifurcated at 100 and engages over a horizontal pin 102 on a post 103. The post 103 is adjustably 60 clamped in a longitudinal slot 104 in the bar 82, the clamping member 105 engaging the upper surface of the bar 82 and fitting in the enlarged slot 106 in the top wall of the guide 83, and the handle 108 for clamping the post to the bar is 65 exposed above the guide 83. The post extends at its lower end, as shown in Figure 6, through a similarly elongated slot 110 in the table 5. To adjust the connection between the upper end of the arm 98 and the bar 82, all that is necessary is to loosen the handle 108 slightly, slide the post 103 through the slot 104 in the desired direction and the desired amount, and again tighten the handle 108. This adjustment is for accom- 70 modating type bars of different lengths and for 75

adjusting the point in the throw of the arm 93 at which the dog 93 is brought into action.

For the purpose of oscillating the arm 98 the shaft 72 is provided with a crank arm 115, and 5 a link 116 pivotally connected at its opposite ends to this arm 115 and to the lever 98 imparts the throw of the crank 115 to the lever 98 to oscillate the same and reciprocate the feed bar 82. This crank connection between the shaft 72 and the lever 98 may obviously be adjustable if desired.

With the parts in the positions shown in Figure 5, the dog 93 is forced inwardly upon reciprocation of the feed bar 82 to the right along the type bar 18 adjacent the guide 83. As the dog 93 passes the right hand end of the adjacent slug 18, it is sprung out by the spring 95 into engagement with the adjacent end of the slug 18 and, upon reciprocation of the bar 82 in the opposite direction, that is, to the left, this engagement of 10 the dog 93 with the adjacent end of the slug 18 takes up this slug and moves it laterally to the left (Figure 5) into the ribbed groove 86, as shown in Figure 8. As the dog 93 reaches the limit of 15 its movement to the left, the slug fed thereby is completely out of the row 18 and the succeeding slug moves up into cooperation with the guide 83 and into registration with the ribbed groove 86.

Upon the succeeding reciprocation of the feed bar 82 the succeeding slug 18 is shifted laterally 20 into the grooved guide 83 and moves the printing head of the preceding slug ahead of it out into the synchronously registered groove in the packing paper or material 12, or out into any 25 other suitable or preferred means, or into position to be taken for use as and where desired. 30 At the limit of the movement of the dog 93 this time the slug is again completely out of the row 18 so that the succeeding slug may be advanced to the guide 83 and the head of the first slug is moved completely out of the guide 23 and packed 35 or positioned to be taken for use.

It will be apparent from the foregoing description that the machine of the present invention is adapted for continuous operation, that is, upon 40 placing a row of slugs in place at 18 upon the table 5 and setting the machine in operation it may continue to operate until the last slug is moved into position in the guide 83 and until the 45 head of the next to the last slug is positioned in the packing material 12 or at the discharge end of the machine. The lateral feed means 22 imparts an intermittent motion to the slugs, the 50 period of intermission in the movement of each slug occurring during the movement of the lateral feed means from its left hand position to its right 55 hand position as viewed in Figure 1. The slug is in position in the guide channel 83 during the period of intermission in its movement and, with the slug in this position and in the embodiment 60 of Figures 1 to 8 during the period of intermission in its movement, it is operated upon to form retention means on the slug and to remove the slug body below the retention means.

For this purpose, I have shown a reciprocable cutter 430 for cutting the shank 30 of the slug to the desired height at 431. This cutter 430 has 65 upstanding protuberances 432 for simultaneously crimping or bending the shank 30 of the slug as shown in Figure 10. An opposed crimping member 433 has a wavy or serpentine edge, as shown in dotted lines at 434 in Figure 9, which is complementary to the protuberances 432 to impart the desired crimped or serpentine formation to the slug shank 30 at a distance below the overhanging head 31. A motion reversing mechanism 70

435 moves the member 433 toward and into co-operation with the crimping protuberances 432 in the crimping operation and in a direction away from the protuberances 432 as the cutter 430 and crimping elements 432 are withdrawn from the slug. This frees the crimped shank 30 for endwise movement of the slug through the guide channel 86. The cutter 430 is guided by guides 438 and is reciprocated by an eccentric 439 disposed on the shaft 55 and surrounded by an eccentric strap 440 to which is connected a pitman rod 441 pivoted at its opposite end at 442 to the cutter 430. The reciprocating crimping member 433 may operate between guides 445.

For the purpose of holding the heads of the slugs down firmly upon the ribs 86' (Figure 8) during the operation of the means for crimping or forming retention means in the shank of the slug and during the operation of the means for removing the slug body below the retention means, a roller 508 is provided. This roller is carried by a frame 509 which operates in a guide 510 and the frame 509 has connection at 511 with a lifting and lowering cam 512 on the shaft 55. The cam 512 is timed to bring the roller 508 down 25 firmly upon the printing face of the slug as the slug crimping and severing means comes into operation, and upon completion of the slug crimping and severing operation the cam 512 lifts the roller 508 to free the crimped printing head of the slug for ejection through and from the guide slot 86. The roller 508, or at least the surface thereof, is preferably of a relatively soft material which will not injure the printing face of the type slug in its engagement therewith.

By moving the slugs through the machine by an intermittent motion and operating upon them during a period of intermission in their movement, the machine may operate continuously to feed successively therethrough a number of slugs 40 placed on the table 5 without interrupting or interfering with the continuous operation of the machine by the operation or operations performed upon the slugs. And the cutting and crimping means operates upon the slugs during 45 the periods of intermission in their movement to crimp the shanks of the slugs below the overhanging heads and to cut off or remove simultaneously the excess of metal below the crimped portion, thereby preparing the slugs for use in the 50 chased carriers of printing machines employing slugs which are less than type high, such as a multigraph drum, slotted type plate or the like.

The crimping of the shank of the slug below 55 the overhanging head produces protuberances on the opposite sides of the shank below the head. These protuberances constitute, in effect, ribs on opposite sides of the slugs which are adapted to be slidingly interlocked with the undercut chases or slots in the drum or type carrier of the printing 60 machine and are effective to lock the slugs to the type carrier and to prevent them from dropping therefrom. The spaces between the overhanging head 31 and the protuberances 450 (Figure 10) on opposite sides of the shank 30 of the finished 65 slug constitute longitudinal grooves for interlocking with the flanges or ribs at the tops of the undercut grooves in the type holder.

I wish to call attention at this point to the fact 70 that, whereas the follower 20 imparts a positive advancing movement to the row of slugs 18, the actuating connection to this follower is yieldable to a degree so that should any of the slugs become jammed or fail to be moved away laterally the machine will continue to operate without 75

injury to any of the parts. For example, the slug advancing dog 45 will simply slip or ride over the toothed bottom 38 of the bar 36 at such time. The other parts of the machine are also free to 5 continue operation without injury in such instances.

The table or base plate 5 has an opening (not shown) through which the severed gate or base of the slug drops down upon and is discharged 10 by a chute 130 and the character bearing head is fed on laterally into the aligned or registered channel in the packing material 12 or holder. For the purpose of aligning and guiding the row 15 of slugs 18 on the left, a guide 135 is secured at 135 upon the top of the table 5.

At the opposite ends of the slugs 18 and adjacent the feed means 22 is an adjustable spacer 140. This spacer 140 comprises a bar 142 mounted upon the table 5 for adjustment in the direction 20 of the length of the slugs 18 to vary the distance between the guide 135 and the opposing end of the spacer 140 to accommodate slugs of different lengths. The spacer bar 142 may be guided by 25 the cooperation of the block 143 with the slot 144 therein, and said bar 142 is adapted to be clamped fixedly in any desired position by the thumb screw 145. The spacer 140 has a yieldable follower plate or bar 148 yieldingly urged by springs 149 into cooperation with the adjacent ends of the 30 slugs 18 to hold the slugs properly positioned between it and the guide 135. Set screws 150 may be provided for adjusting the yieldable follower plate 148 with respect to the spacer bar 142.

Pivoted on the slug cooperating end of the 35 bar 142 upon a pivot 152 to swing in a horizontal plane is an arm 154. This arm 154 forms, in effect, a kick-over member which engages the slug 18 adjacent the guide 83 as the slug is registered with the groove 86 and kicks the slug laterally 40 slightly as shown at 158 in Figure 5. This initially engages the head of the slug in the groove 86 and sets the opposite end of the slug in a little just preceding its lateral movement which assures that the pivoted dog 93 will take over this 45 end of the slug and shift the same laterally with its succeeding reciprocation. For its kick-over action, the arm 154 is provided with a reduced nose 160 (Figure 5) which engages only one slug adjacent the guide 83 at a time. The arm 154 is urged in a counterclockwise direction (Figure 5) by a coiled spring 162 so that as the head of the 50 slug is freed by its registration with the slot 86 the arm 154 is swung in a counterclockwise direction and, by means of its nose 160, moves the slug laterally slightly.

The corrugated packing material or the galley, multigraph drum, segment, or other holder or receiver, as the case may be, may be operated or advanced synchronously with the follower 20 and reciprocating bar 82 to register successively the channels 132 with the channel 86 for the reception of the type slugs with each reciprocation of the bar 82 to the left in Figure 1.

Where the slug receiver is the packing material 65 or board 12, the mechanism 15 for advancing the corrugated paper or board 12 over the upper surface of the table 5 parallel with the feed by the follower 20 and at right angles to the lateral feed by the reciprocating bar 82 operates synchronously 70 with the follower 20 and reciprocating bar 82 to position one of the longitudinal depressions or valleys 132 in the corrugated paper in register with the slot 86 for the reception of the type carrying head of the bar with each reciprocation of the bar 82 toward the paper 12. As the bar 82

moves to the right (Figure 1) a corrugation or valley in the packing material is moved into register with the opposite end of the slot 86 and remains in registration therewith to receive the character bearing head of the type bar upon 5 movement of the bar 82 to the left (Figure 1), whereupon the corrugated paper 12 is again advanced to position the succeeding vale or corrugation in register with the slot 86 to receive the succeeding type bar head. In this manner, all 10 that is required is to place the type bars upon the table 5 between the follower 20 and the guide 83 and the follower 20 operates to register successively these bars with one end of the slot 86, while the feed mechanism 15 operates to register 15 successively the corrugations with the opposite end of the slot 86 and the feed mechanism 22 operates to feed the bars laterally and by intermittent motion into the guide slot 86, and the character bearing heads of the bars are then 20 moved from the guide 86 and into the corrugations in the packing material. The bars in the row 18 may be conveniently replenished from time to time by drawing the follower 20 forwardly and inserting additional bars ahead of 25 the same, the spring action in the feed means for the follower 20 permitting the forward withdrawal of the follower for this purpose.

The paper feed mechanism 15 is fully illustrated and described in the parent application 30 above identified. It forms no part of the present invention and full illustration and description thereof will not be repeated here. Where reference characters are supplied to parts of the paper feed mechanism, these reference characters 35 designate similarly designated parts in the parent application, and reference is made to that application for a description of these parts and for such additional disclosure as may be desired.

It is to be understood that, instead of placing 40 the slugs upon the table 5 of the machine in type high form and simultaneously crimping the shanks of the slugs beneath the heads and removing the shanks below the crimped portions, the slugs may, within the scope of the present 45 invention, be cut or formed to the desired height for use in the chased carrier of the printing machine, and the less than type high slugs may be moved through the machine in a given path and operated upon in the movement in said path to 50 form the retention means thereon.

It is to be further understood that, instead of cutting the slugs to the desired height by operating upon them across their width and during a period of intermission in their movement, the 55 shanks of the slugs may be operated upon during their movement through the machine by a rotary cutter 460 (Figure 11) disposed in the path of travel of the slugs and adapted for cutting the shanks of the slugs to the desired height.

And the present invention is not limited to forming the retention means by operating upon the slug across its width and during a period of intermission in its movement. As shown, for example, in Figures 12 and 13, the retention 65 means may be formed in the shank of the slug at a distance below the overhanging head by complementary crimping wheels 465 rotatable in opposite directions about axes 466 and provided with complementary wavy or serpentine peripheries 467 between which the slug shank passes and is bent or crimped to the desired form in the movement of the slug through the machine. Where the slug is originally type high or of a height greater than the height adapted for use 70 75

in the multigraph drum or other carrier, the crimping wheels 465 and cutter 460 are combined in the same machine to crimp the shank of the slug and to remove the shank below the crimped part in the movement of the slug through the machine. If the slug is cut or formed to the desired reduced height for use in the multigraph drum or other carrier before delivery to the machine, the cutter may be omitted, in which case the crimping wheels 465 will operate to crimp the shank a distance below the head in the passage of the slug through the machine.

In Figure 14 I have shown a block 450 which is adapted to be mounted in the opening in the bed of the machine in place of the block 23 and associated parts. This block 450 has a channel 451 for receiving the slug 452 which is shown as being without grooves or the like. An underlying plate 453 fastened to the block 450 supports the bottom of the slug 452 and the printing base of the slug is provided with a rule 455 disposed up in an overlying block 456 which is undercut at 457 to receive bits 458.

The bits 458 form broaching bits and are of the usual triangular cross-section, and they are suitably connected as through an eccentric mechanism with one of the drive shafts of the machine, for example, the shaft 55 to be reciprocated thereby and broach the printing rule 455. For the purpose of permitting the eccentric connection, the bed plate is provided with suitable slots 460, as shown in Figure 1, the slug 452 with the rule 455 broached at 465 is shown fragmentarily in Figure 15. The broached openings 465 are positioned at suitable intervals along the rule 455 so that, when a plurality of the slugs 452 are assembled in side-to-side relation with the openings 465 in alignment, cross rules or tie strips of corresponding triangular cross-section may be inserted through the aligned triangular openings 465 to position the cross rules to print lines across the lines printed by the rules 455. The printing feature of the cross rules may, of course, be omitted, in which case the tie strips inserted through the broached openings 465 will tie the assembled slugs 452 together to hold the same in printing relation.

I have described the invention in connection with the details of certain particular embodiments, but I do not intend thereby to limit the invention to such details, nor do I intend to be limited to the particular relation of the essential features shown and described.

I claim:

1. In a machine of the class described, the combination of a continuously operating reciprocatory means for moving a printing slug by intermittent motion in a given path, and movable means operable with said continuously operating means during a portion of its reciprocatory movement but during a period of intermission in the movement of the slug and constituting a part of the machine for operating upon the slug in a direction transverse to the normal movement of the slug in said path to form retention means on the slug.

2. In a machine of the class described, the combination of a continuously operating means for moving a printing slug by intermittent motion in a given direction, said slug having a slug body, separate means operating continuously in conjunction with said first means for moving said slug laterally with respect to said direction in

which the slug is moved by said first means, and means operable in a direction parallel with respect to said first direction and with said first continuously operating means and constituting a part of the machine for operating upon the slug across its width and during a period of intermission in the movement of the slug to form retention means on the slug and to remove the slug body below the retention means. 5

3. In a machine of the class described, the combination of means for supporting a group of slugs, each of which is provided with a shank and a T-shaped head, means disposed alongside said supporting means and positioned with respect to said first supporting means for supporting one 15 slug at a time by the T-shaped head thereof, a continuously operating means for moving said slugs by intermittent motion in a given path and advancing said slugs, one at a time, from said first supporting means to said second supporting 20 means, and means operable with said continuously operating means for operating upon the slug held in said second supporting means during a period of intermission in the movement of the slugs to bend the slug held in said second supporting means some distance below the T-shaped head thereof whereby to form retention means 25 on the slug. 25

4. The method of preparing a group of printing slugs for use in a chased carrier of a printing machine, each of said slugs having a slug body, which method comprises advancing the group of slugs in a given direction, intermittently shifting the slugs laterally one at a time from said group in a direction toward a receiver, operating upon each slug in the direction parallel to said first direction after the slug has been shifted laterally from said group but before it has reached said receiver for the purpose of forming retention means on the slug and to remove the 40 slug body therefrom below the retention means, and completing the movement of the printing slug to said receiver in said second direction. 30

5. In a machine of the class described, the combination of a continuously operating means 45 for moving a printing slug by intermittent motion in a given path, a pair of operative means arranged on opposite sides of the portion of said given path in which the slug has its position during the period of intermission in the intermittent movement of said slug, and means for moving said pair of operative means simultaneously in opposite directions and at right angles to said portion of the path to operate on both sides of said slug while in said position to form retention 55 means on the slug. 50

6. In a machine of the class described, the combination of a continuously operating means for moving a printing slug by intermittent motion in a given path, a pair of operative means 60 arranged on opposite sides of the portion of said given path in which the slug has its position during a period of intermission in the intermittent movement of said slug, means for moving said pair of operative means simultaneously in opposite directions and at right angles to said portion of the path to operate on both sides of said slug while in said position to form retention means on the slug, and means operated by said last mentioned means for holding said slug in said position during the formation of said retention means thereon. 65

HARLEY J. MEGLEY.
